(57) **CLAIM**

The ornamental design for a pineapple holder, as shown and described.

DESCRIPTION

FIG. 1 is a perspective view of a pineapple holder showing the new design.

FIG. 2 is a top view of the pineapple holder of FIG. 1.

FIG. 3 is a bottom view of the pineapple holder of FIG. 1.

FIG. 4 is a front view of the pineapple holder of FIG. 1; and,

FIG. 5 is a side view of the pineapple holder of FIG. 1.

The broken lines are for illustrative purposes only and form no part of the claimed design.
